UNITED STATES PATENT OFFICE.

MARTIN R. SCHNACK, OF LOS ANGELES, CALIFORNIA.

DESIGN FOR A DOLL.

Application filed December 29, 1920. Serial No. 433,948. Term of patent 3½ years.

To all whom it may concern:

Be it known that I, MARTIN R. SCHNACK, a citizen of the United States of America, residing at the city of Los Angeles, in the county of Los Angeles and State of California, have invented a new, original, and ornamental Design for Dolls, of which the following is the specification, reference being had to the accompanying drawing, forming a part thereof.

I claim:

The ornamental design for a doll, as shown.

MARTIN R. SCHNACK.
